DESIGN FOR A FISHING LURE

Nelia G. Poplin, Ponca City, Okla.

Application May 23, 1945, Serial No. 119,678

Term of patent 14 years

(Cl. D31—4)

To all whom it may concern:

Be it known that I, Nelia G. Poplin, a citizen of the United States, residing at Ponca City, in the county of Kay and State of Oklahoma, have invented a new, original, and ornamental Design for Fishing Lure, of which the following is a specification, reference being had to the accompanying drawing, forming part thereof.

Figure 1 is a plan view of a fishing lure showing my new design.

Fig. 2 is a side elevational view thereof, the side of the fishing lure opposite to that shown in this view having the same appearance.

Fig. 3 is an end elevational view thereof.

I claim:

The ornamental design for a fishing lure, as shown and described.

NELIA G. POPLIN.
